US00D768282S

(12) **United States Design Patent** (10) **Patent No.:** **US D768,282 S**
Cardoso et al. (45) **Date of Patent:** **** Oct. 4, 2016**

(54) **STRUCTURAL SUPPORT FOR SOLAR ENVELOPE AND SOLAR COLLECTOR**

(71) Applicant: **ALVA ALTA**, Lisbon (PT)

(72) Inventors: **Paulo A. Cardoso**, Lisbon (PT); **Daniel Caramelo**, Lisbon (PT)

(73) Assignee: **ALVA ALTA LDA**, Lisbon (PT)

(**) Term: **15 Years**

(21) Appl. No.: **29/528,200**

(22) Filed: **May 27, 2015**

(51) LOC (10) Cl. **23-03**

(52) U.S. Cl. **USPC D23/386**

(58) **Field of Classification Search**

USPC D14/356; D10/93, 104.1, 108, 114; D8/4, 25, 52; D17/20, 22, 23; D23/323, 328, 333, 335, 336, 337, 341, D23/352, 357, 370, 385, 386, 397, 399, 400, D23/406, 411, 413, 499; D11/143, 144

(57) **CLAIM**

We claim the ornamental design for the structural support for solar envelope and solar collector, as shown and described.

DESCRIPTION

FIG. 1 is an elevated, perspective view of the structural support for solar envelope and solar collector showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 6 Drawing Sheets
